UNITED STATES PATENT OFFICE.

HARRY C. DOANE, OF FLINT, MICHIGAN, ASSIGNOR TO GENERAL MOTORS CORPORATION, OF DETROIT, MICHIGAN, A CORPORATION OF DELAWARE.

DESIGN FOR A VEHICLE LAMP DOOR.

Application filed June 13, 1927. Serial No. 22,419. Term of patent 14 years.

To all whom it may concern:

Be it known that I, HARRY C. DOANE, a citizen of the United States, residing at Flint, in the county of Genesee and State of Michigan, have invented a new, original, and ornamental Design for a Vehicle Lamp Door, of which the following is a specification, reference being had to the accompanying drawing, forming part thereof.

Fig. 1 is a plan view of a vehicle lamp door of my new design.

Fig. 2 is a side view thereof.

I claim:

The ornamental design for a vehicle lamp door as shown.

HARRY C. DOANE.
